UNITED STATES PATENT OFFICE.

CABEL B. HOPKINS, OF LOUISVILLE, KENTUCKY, ASSIGNOR TO THE HOPKINS & ROBINSON MANUFACTURING COMPANY, OF SAME PLACE.

MONEY-CHANGER.

SPECIFICATION forming part of Letters Patent No. 339,986, dated April 13, 1886.

Application filed June 30, 1885. Serial No. 170,266. (No model.)

To all whom it may concern:

Be it known that I, CABEL B. HOPKINS, of Louisville, in the county of Jefferson, and in the State of Kentucky, have invented certain new and useful Improvements in Money-Changers; and I do hereby declare that the following is a full, clear, and exact description thereof, reference being had to the accompanying drawings, in which—

- 10 Figure 1 shows a perspective view of my apparatus with some portions of the casing removed, and others broken away to show the operative parts more clearly; Fig. 2, a view of the same in rear elevation, the rear side of the casing being removed; Fig. 3, a vertical sectional view of the apparatus on line $x-x$ of Fig. 1; Fig. 4, a detail view in front elevation of the lower portions of the operative levers with the lugs thereon, and Fig. 5, a detail 15 view in rear elevation of the coin-tube supporting-bar.

Letters of like name and kind refer to like parts in each of the figures.

The object of my invention is to provide an improved automatic money-changer; and to this end it consists in the construction, arrangement, and combination of parts, as hereinafter specified.

In the drawings, A designates the casing, 30 which, as shown, is preferably formed with the upper portion, A', extending forward over the front of the lower portion. The top B of the casing is hinged at its rear edge to the top of the rear of the casing, and is to be provided 35 with any desired form of lock for fastening it shut.

Fitting and fastened within the casing is the frame C, preferably of metal, and consisting of the bar C', extending across the rear of the 40 casing interior, and the side pieces, C² C², attached to or made in one piece with the bar C'. These pieces are attached by means of screws to the sides or ends of the casing, as shown. One arm, c, of each of these pieces 45 extends upward and forward, and supports one end of the plate or flat bar D, situated near the front of the casing. In this plate are openings for admitting the passage of coins of different denominations. They can be of any 50 desired number; but I prefer that there should be seven, one of a size to admit the passage of

a dollar, the next of the right size for a half-dollar, the next for a quarter, the next two for a ten-cent coin or dime each, the next for a five-cent piece, and the last for a cent. To 55 the plate D, above and concentric with these openings, coin-holding tubes of diameters corresponding with the respective coins can be fastened. I prefer to split the coin-holding tubes longitudinally, as shown in the drawings, and fasten to the plate D only the rear halves of the tubes E E, as shown in the drawings. The front halves, E' E', are attached at their upper ends to the hinged top B, so that when the top is down in place the front halves 60 of the tubes will be brought and held in place to complete the tubes, and hold the coins therein securely in place. With this construction, when the top is swung up the coins of any one denomination can be put in all together in a pile or roll in a quantity to fill the tube. This saves much of the time which is necessary where the coins are fed into the tube by dropping them into place separately from above. 75

To allow of feeding the tubes from the top when desired without unlocking and swinging the top B up, I provide on such top a plate, F, formed with slots f f over the tubes below, and, for convenience, mark the slots with numbers indicating the denomination of the coins to be dropped through them, respectively. 80

Fastened to the bottom of plate D is the second plate, G, formed with the downward offsets g g, below the several coin-openings in plate D. A single offset is made extensive enough for both the ten-cent-coin openings, and for the five and one cent openings. The plate G is fastened to plate D by means of screws or rivets passing up through its portions between the offsets. In each offset, except the double ones below the dime and the five and one cent openings, fits and moves a coin-delivering slide, H, similar in construction and action to the delivering slides shown 90 and described in my Patent No. 288,942, of November 20, 1883. In each of the double offsets below the openings named two delivering-slides, H H, one for each opening, fit and slide side by side. 95

For allowing the passage of the coins taken from the coin-holders, the plate G is, like the 100

lower plate of the coin-holder supporting bar, as shown and described in my patent referred to, cut away at its forward edge, so that when a coin has been moved forward from the pile 5 in the tube by the slide it can fall freely downward.

Below the plate G and extending across the apparatus is the hopper I, adapted to catch the coins delivered from any of the holders. 10 The bottom of this hopper slopes toward the center of the apparatus from each side, as shown. The lowest contracted portion of the hopper projects down from the overhanging portion of the casing, as shown, and is provided with a swinging trap or valve, I', hinged at its rear side. This is provided with the handle I'', and is normally kept swung up against the hopper-mouth to close it by the spring i, drawing down on the arm i', extending rearward from the trap. Said trap or valve is preferably turned up at its sides to form a trough or guide for coins sliding down over it when it is swung down.

In the downwardly-extending arms c' c' of 25 the two side pieces, C' C'', are supported the opposite ends of the rod or fixed shaft K, upon which are pivoted the levers L L L. for operating the coin-delivery slides H H H, one for each slide. The upper end of each lever is 30 connected with its slide preferably by bending a portion of the lever backward and upward, and then over the rear end of an arm, h, on the slide, and then passing a pin, h', down through the overhanging upper end of 35 the lever and the arm of the slide. Other means and other ways of connecting the levers and slides can, however, of course be used, as desired.

To lock the levers from possible movement, 40 when desired, I provide the swinging lock-bar L', consisting of the horizontal bar having its ends turned at right angles to the rest of the bar and pivoted to the sides of the casing at l and l, just in rear of the coin-holders and 45 above the slides. When this lock-bar is swung down, as shown in full lines in Figs. 2 and 3, it engages the upper ends of the levers. When swung up, as shown in dotted lines in Fig. 3, the lock-bar rests against the coin-holders and 50 leaves the levers free to operate the slides.

For keeping the levers normally swung back and to retract them when moved forward to actuate the slides, I provide the springs M M, one for each lever, attached at their forward ends to the upper arms of the levers and at their rear ends to bar C'.

At the front of the casing and near its bottom is the frame N, extending across the casing from side to side and projecting inward from 60 the casing-front. This frame is preferably cast in one piece, and consists of the upper and lower parallel front bars, N' N'', and the upper and lower parallel rear bars, N' N'', nearer each other than are the front bars. At 65 the ends of the frame the bars thereof are connected together by a plate or web, as indicated best in Fig. 1. At the ends of the frame are

the attaching lugs or arms n n, turned outward and adapted to be attached by screws or otherwise to the casing, as shown. At equal 70 intervals apart the rods O O pass back loosely through openings in the upper front plate, N'. After passing through this plate they are bent downward at a right angle, and then rearward at a right angle, and their rear ends pass 75 loosely through openings in the lower rear plate, N''. The forward ends of the slides thus formed are provided with finger disks or plates O' O', each marked with a number indicating a certain amount of change. A second series of slides similarly shaped is provided below. The rods forming the shanks of these slides pass inward or rearward through plate N'', then upward, and then rearward through holes in plate N''. These slides or 80 sliding keys are, like the others, provided with disks or plates O' O', marked with numbers also indicating various amounts of change.

As shown in the drawings, the key to the left of the upper series is marked with 1, indicating one cent, and the others are marked successively 10, 20, 30, &c., up to 100. The other keys below are marked from 5, 15, 25, &c., up to 95. This particular way of numbering is, however, not essential, though very 95 convenient.

The upright portions of the rods forming the keys are utilized to operate the proper levers to cause the right combination of coins to be delivered as the keys are pushed in, in 100 the manner to be described hereinafter.

The rods of which the keys are formed are preferably made, as shown, angular in cross-section, the guide-openings in the plates of frame N being correspondingly shaped. The 105 forward or outward movements of the keys are limited by the upright portions of the keys striking the forward plates through which the keys extend, as indicated best in Fig. 3.

Upon the lower end of the lever connected with the one-dollar delivery-slide is a lug, P, extending forward so as to be engaged by the upright portion of the 100-key, as such key is pushed in. The fifty-cent lever is, below 115 its pivotal point, extended downward and sidewise to a point to the farther side of the fifty-cent key, then is bent back and extends horizontally along behind the keys to a point beyond the one-dollar lever and key. It is 120 then bent upward, and the upper end of this vertical part L' is pivoted upon the rod K, as shown.

Upon the horizontal portion L' of the lever is the lug P', extending forward to or nearly 125 to the upright portion of the fifty-cent key. The upright part of the lever could be dispensed with, if desired; but I prefer the construction and formation as described, as preventing possible twisting and binding of the 130 lever on the pivot-rod. The next lever, which is the twenty-five-cent lever, is similarly formed, being carried out to the side a little beyond the line of the twenty-five-cent key, and then

back below the horizontal portion of the fifty-cent lever, and upward. The successive levers are thus formed throughout the series, each successive lever extending beyond and having its horizontal portion below that of the preceding lever, except the last or one-cent lever, which, like the one-dollar lever, has on its lower end simply a forwardly-extending plate or lug, P, adapted to be engaged by the one-cent key alone.

As the horizontal portions of all the levers, from and including the five-cent lever to and including the ninety-five-cent lever, extend along behind their respective keys and all the successive higher keys, where it is desired to operate several of the levers at once to make the desired amount of change, this can be easily arranged for by putting on the horizontal portions of such levers, in line with the upright portion of the key, lugs to be engaged thereby when the key is pushed in. This is the construction which I prefer. Behind the fifteen-cent key the ten and the five cent levers are provided with lugs to be engaged by the key, so that the two levers will be operated at once to take and deliver a ten-cent and a five-cent coin. The two ten-cent levers are provided with lugs behind the twenty-cent key. Behind or in line with the twenty-five-cent key there is a lug on the twenty-five-cent lever alone.

To describe the arrangement of the lugs on all the levers, briefly, the five-cent lever is provided with lugs adapted to be engaged by the five, fifteen, thirty, forty, fifty-five, sixty-five, eighty, and ninety cent keys. The first ten-cent lever has lugs behind the ten, fifteen, twenty, thirty-five, forty, forty-five, sixty, sixty-five, seventy, eighty-five, ninety, and ninety-five cent keys. The second ten-cent lever in the series has lugs to be engaged by the twenty, forty-five, seventy, and ninety-five cent keys. The twenty-five-cent-lever has lugs for the twenty-five, thirty, thirty-five, forty, forty-five, seventy-five, eighty, eighty-five, ninety, and ninety-five cent keys. The fifty-cent lever has a lug to be engaged by all the keys from and including the fifty to and including the ninety-five cent keys.

I do not limit myself to the particular arrangement of lugs on the levers with respect to the keys, as set forth above, as the lugs may, if desired, be arranged so that different combinations of levers will be operated to deliver different combinations of coins sufficient to make up the desired amount of change. I prefer, however, the construction and arrangement described and shown.

The spring i, which serves to keep the flap or valve I' closed up against the hopper-mouth to retain any change in the hopper until it is swung down by the operator taking hold of the handle I², has its lower end attached to bar N', as shown.

The operation of my machine is as follows: If, for instance, change to the amount of ninety-five cents be desired, the ninety-five key is

pushed in and its upright portion engages the lugs on the fifty, twenty-five, and two ten-cent levers, and such levers are actuated to 75 take single coins from their respective coin-tubes or holders and deliver them down into the hopper, where they fall and rest upon the flap or valve until taken therefrom by the operator. If change to the amount of forty 75 cents is desired, the forty-lever is pushed in and as it engages lugs on the twenty-five, ten, and five cent levers such levers are actuated, and a twenty-five, a ten, and a five cent piece are delivered. From this description the action of the rest of the keys and levers will be clearly understood.

If desired, the number of keys can be increased, and combinations of a dollar with the other coins can be caused to be delivered where 85 desired, the dollar-lever being provided with suitable lugs like the other levers, as described, and the horizontal portions of such levers being made more extensive, to accommodate the increased number of lugs necessary for the increased number of keys. In the same way, if desired, the apparatus might be adapted to deliver amounts of change made up of the coins of other denominations and cent coins; but as this would necessitate largely increasing 95 the number of keys, I prefer the apparatus as described and shown.

The lugs on the levers normally engage the rear sides of the upright portions of the keys. As the lower portions of the levers carrying 100 such lugs are normally kept swung forward by the springs M M, the keys will be kept pushed out to the limit of their outward movement, and will always be returned to such outward normal position by the action of the 105 springs on the levers when they have been pushed in.

When the changer is not be used, the top can be unlocked and swung up, and the lock-bar L' can then be dropped down into place 110 to lock the levers. When the top is locked again, change cannot be obtained, except by one having the key to enable him to swing the bar up again.

I contemplate, when desired, providing a 115 catch within the casing to hold the lock-bar up or down.

At the front of the casing, to cover over the frame N and the opening in the casing-front therefor, I fasten the plate S, preferably of 120 German-silver, brass, or other ornamental metal, provided with suitable openings for the passage of the push-keys.

Instead of the slide form of device for taking and delivering a coin from a holder or 125 tube, I contemplate using any other desired form of feed or delivery device adapted to be operated by the actuating-lever. From the mouth of the hopper a tube or trough can be extended to carry and deliver the coins from 130 the hopper at any desired point.

Obviously, if desired, each of the keys can be formed of a pivoted lever in the well-known way, instead of a sliding piece, and such

change would not involve any departure from my invention. The levers could be properly actuated by swinging or pivoted keys, whether the latter were pivoted above or below. Arms 5 from such levers would project out through the front side of the casing in the same way as the outer ends of the sliding keys.

I do not intend herein to limit myself to the sliding or any particular form of movable operating-key. I have shown and described lugs so situated on the actuating-levers for the delivery-slides that the keys when moved would engage such lugs and operate a combination of the levers at once or together. If desired, 15 this construction can be reversed, and instead of the lugs being on the levers they can be placed on the movable keys so as to gain the same end—viz., the operation of several levers at a time. Such mere reversal of my construction would of course involve no departure from my invention as covered by my claims.

Having thus described my invention, what I claim is—

1. In combination with two or more coin-delivering devices and levers connected therewith to operate the same, a movable key adapted to operate the several levers, substantially as and for the purpose described.

2. In combination with several coin-holders and delivery devices acting in connection therewith, levers for actuating such devices and a movable key so connected with the several levers as to operate them together, substantially as and for the purpose described.

3. In combination with the series of coin-holders and coin-delivery devices acting in connection therewith, the series of levers for operating the delivery devices and a series of keys, each one adapted to operate a combination of two or more of the levers as it is moved, substantially as and for the purpose described.

4. In combination with two or more of the levers for actuating the coin-delivery devices of a money-changer, a movable key and suitable connecting means between the levers and the key, whereby as the key is moved the several levers will be actuated, substantially as and for the purpose described.

5. In combination with two or more coin-delivery devices and levers connected therewith to actuate the same, a movable key adapted to engage portions of the levers to actuate several levers at the same time, substantially as and for the purpose described.

55 6. In combination with an actuating key, two or more levers provided with lugs or projections to be engaged by the key when it is moved and separate coin-delivery devices connected with and operated by the levers, substantially as and for the purpose described.

7. In combination with a series of actuating-keys, a series of levers connected with and actuating coin-delivering devices, and provided with lugs or projections so situated that as a 65 key is moved one or more levers will be actuated to deliver together a combination of coins, such as to make up the desired amount of

change, substantially as and for the purpose described.

8. In combination with a series of separate coin-delivery devices, the series of levers connected therewith, provided with lugs and movable keys adapted to engage the lugs on two or more of the levers at a time, so as to move such levers, substantially as and for the purpose described.

9. In combination with a series of coin-holders and the series of separate coin-delivering devices for taking and delivering coins from the same, the series of levers connected with such devices, the series of movable keys, some adapted to engage portions of single levers to operate such levers singly, and others adapted to engage portions of two or more of the levers together, to cause combinations of coins 85 to be delivered to make up different amounts of change, substantially as and for the purpose described.

10. In combination with the series of coin-holders and the delivery devices therefor, the series of push-keys and the series of levers for actuating the coin-delivery devices, having the horizontal portions behind the series of keys provided with lugs adapted to be engaged by the keys as the latter are pushed in, substantially as and for the purpose described.

11. In combination with the series of push-keys suitably marked to indicate different amounts of change, the series of coin-holders, the series of coin-delivering devices therefor, the series of levers for actuating such devices, provided with arms or portions behind the series of keys, and lugs on such arms or portions so situated that as any key is pushed in it will engage the lug on the proper lever or the lug on the proper combination of levers, according as it is a key designated by the amount of one coin or of several combined, substantially as and for the purpose described.

12. In combination with the two holders for ten-cent coins and the two delivery devices therefor, the two levers connected with such devices, the ten and the twenty cent keys, the lug on one of the levers adapted to be engaged by the ten-cent key, and the lug on each lever adapted to be engaged simultaneously by the twenty-cent key, substantially as and for the purpose described.

13. In combination with the coin-holders and the devices for taking coins separately therefrom, the series of push-keys suitably numbered to indicate the different coins and amounts made up of combinations thereof, the levers for actuating the coin-delivery devices and adapted to be operated singly by the respective keys indicated by the amounts of single coins, and together in proper combination to deliver several coins to make up other amounts of change by the other keys, substantially as and for the purpose described.

14. In combination with a front and rear guide-plate, the push-key consisting of the forward and rear portions passing through and guided in the front and rear plates, respect-

ively, and the part connecting such portions substantially at a right angle thereto, substantially as and for the purpose described.

15. In combination with the frame having the upper and lower front plates and the upper and lower back plates, the series of push-keys consisting of rods passing in through the upper front plate, then bent downward, and at their rear ends passing through the lower back plate, and the series of similarly-formed inverted keys having their forward ends passing through the lower front plate and their rear ends through the upper back plate, substantially as and for the purpose described.

15 16. In combination with the series of push-keys, the series of coin - delivery devices and the actuating - levers therefor having lugs or projecting portions adapted to be engaged by and normally resting against the push - keys,

and the springs for returning the levers to their 20 normal positions after they have been moved by any of the keys, substantially as and for the purpose described.

17. In combination with the coin - holder support and the lid of the casing, the stationary half-tubes attached to the coin-holder support and the half-tubes attached to the lid and adapted to form with the stationary half-tubes whole tubes when the lid is down, substantially as and for the purpose described. 25 30

In testimony that I claim the foregoing I have hereunto set my hand this 18th day of June, A. D. 1885.

CABEL B. HOPKINS.
